P. J. DREHER.
STOP MEANS FOR SHEET HANDLING APPARATUS.
APPLICATION FILED OCT. 16, 1914.

1,143,369.

Patented June 15, 1915.

UNITED STATES PATENT OFFICE.

PHILLIP JACOB DREHER, OF TOLEDO, OHIO.

STOP MEANS FOR SHEET-HANDLING APPARATUS.

1,143,369.

Specification of Letters Patent. Patented June 15, 1915.

Application filed October 16, 1914. Serial No. 968,944.

To all whom it may concern:

Be it known that I, PHILLIP JACOB DREHER, a citizen of the United States, and a resident of Toledo, in the county of Lucas and State of Ohio, have invented a certain new and useful Stop Means for Sheet-Handling Apparatus; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates particularly to stop means for sheet printing or feeding apparatus.

The primary object of my invention is the provision in combination with an actuating mechanism for a sheet printing or feeding apparatus of means which is pneumatically operable to stop the actuating mechanism when the last sheet of a pile or set has been acted on by the apparatus.

Further objects and advantages of the invention will be apparent from the following description.

The invention is fully described in the following specification and while in its broader aspect it is capable of embodiment in numerous forms a preferred embodiment thereof is illustrated in the accompanying drawings, in which,—

Figure 1 is a diagrammatical arrangement of a portion of an apparatus embodying my invention. Fig. 2 is a front elevation of the sheet holding table with parts broken away, and Fig. 3 is a section of one of the pneumatically controlled operating units of the invention.

Referring to the drawing, 1 designates a sheet holding table, which, in the present instance, is disposed on an incline and may be associated with a typewriter or other apparatus to which sheets are intended to be intermittently fed. The table 1 is intended to support a plurality of sheets of paper or other material, one over another in pile form and has associated therewith a mechanism for successively or intermittently feeding the sheets of a pile from the table, the feeding taking place from the top of the pile.

The feeding mechanism for the sheets may be similar to that described in my prior

United States Letters Patent, No. 1,070,021, dated August 12, 1913, or it may be of any other suitable character as desired. The sheet feeding mechanism illustrated in the present instance comprises one or more arms 2, which are pivoted to the table, and carry a hollow shaft 3 at their free or swinging ends. The shaft 3 is provided with one or more laterally projecting picking-up mouth-pieces 4, which are in communication through the hollow shaft 3 and a tube 5 with a suction conduit 6. The conduit 6 has a suction creating device 7 disposed therein, which device is operated in the present instance by an electric motor 8. A spring 9 acts on each arm 2 to normally retain it in outwardly swung relation to the table so that the sheet picking up cups 4 normally stand at the outward limit of their rocking strokes.

The arms 2 in the present instance are two in number, as shown in Fig. 2, and are rigidly connected together by a cross-bar 10, one end of which cross-bar is connected by a rod or link 11 to the movable part 12 of a pneumatic operating unit 13. There are numerous forms of these pneumatic operating units on the market and it will be sufficient for an understanding of the operation of the invention to describe one form, only thereof, which is shown in detail in Fig. 3. In this figure 14 designates the body or stationary part of the unit, and 15 the interior of the bellows or collapsing portion of the unit. The body 14 is provided with a chamber 16, which has a passage 17 in communication with a suction means, as, for instance, the suction device 7. The chamber 16 also has communication with the interior of the bellows 15 through a passage 18. A diaphragm 19 is disposed in the chamber 16 and divides it into two compartments, one of which has communication with both passages 17 and 18, while the other has valve controlled communication with the atmosphere through a passage 20, as hereinafter more fully described. A disk-valve 21 is disposed in the passage 18, and has its stem projected into the chamber 16 and attached to the diaphragm 19. When the valve is raised by suction action thereon from within the chamber 16 it closes the communication between such chamber and the passage 18, and when the valve is lowered, due to atmospheric pressure in the passage 20 upon the diaphragm 19, it is lowered and opens the communication between the chamber 16

2
and passage 18 and closes the opening 22 from the passage 18 to the atmosphere. It is thus apparent that when the passage 20 in the operating unit is opened to the atmosphere, atmospheric pressure will rush into said passage and act on the diaphragm 19 to force the valve 21 to open the passage 18 to the chamber 16, thereby permitting an immediate exhaust of air from the interior 5 of the bellows part 15 due to the suction action within the chamber 16, and effecting a consequent sudden collapsing of the movable part 12 of the unit. A small bleed opening 23 is provided between the passage 10 20 and suction chamber 16 to permit any air remaining in the passage 20, after a closing of the same to the atmosphere, to be slowly drawn therefrom into the suction chamber 16 to relieve the pressure on the 15 side of the diaphragm 19 opposed to the valve.

In the present arrangement, the suction passage 17 of the unit 13, which serves to communicate inward swinging movements 20 to the arms 2, has connection through a tube 24 with the suction conduit 6, and the passage 20 of the unit has communication through a tube 25 with one of the passages of a tracker 26, over which tracker 25 a master control sheet 27 operates, as is well understood in the art. When a perforation in the master-sheet 27 moves into register with the passage in the tracker 26 with which the tube 25 communicates, communication is established between the atmosphere and the passage 20 of the associated operating unit thereby effecting a movement of the valve 21 of the unit to open the passage between the suction device 30 and the interior of the bellows 15 and effect an inward or collapsing movement of the movable part 12 of the unit 13. The movement thus imparted to the part 12 is communicated through the rod or connecting member 11 to the arms 2 and moves such arms and the picking up mouth pieces 4 inward to sheet engaging or picking up position. When the communication between the passage 20 and the atmosphere has been closed 40 the collapsing part 12 is relieved of the suction action within the chamber 16 of the unit and is permitted to open under the action of the springs 9 on the arms 2. A coiled compression spring 28 is disposed between the bar 10 and the outer headed end 45 of the rod 11 to cushion the thrust action of the rod 11 on said bar and also to provide a yielding connection therebetween to compensate for a varying of the thickness 50 of a pile of sheets being acted on.

The tube 5 which opens communication between the picking up cups 4 and the suction conduit 6 has a valve 29 disposed therein and normally standing in position to 60 close the passage through the tube. A stem

30 projects from the valve 29 without its casing and has connection through a link 31 with the movable part 32 of a pneumatic operating unit 33, which unit is preferably of the same construction as the unit 13 and 70 has its suction passage 17 in communication through a tube 34 with the suction conduit 6, and its passage 20 in communication through a tube 35 with a passage in the tracker 26. The valve 29 is normally held 75 in passage closing position by a coiled compression spring 36 and is moved to open position against the tension of said spring by a collapsing movement of the movable part 32 of the operating unit 33. The collapsing of the bellows part 32 of the unit 33, which is controlled by the perforations in the master sheet 27, is timed to take place when the picking up mouth pieces 4 have swung inwardly into contact with the 80 upper sheet of a pile disposed on the table 1 so that the valve 29 will be opened to permit a suction to take place through the tube 5 and mouth pieces to hold the engaged sheet to the mouth pieces. When the mouth pieces 4 have swung outwardly with the arms 2 the engaged sheet is picked up and 85 swung outwardly therewith and is then released to permit it to have a forward feeding movement due to the closing of the 90 valve 29.

37 designates the movable member of an electric switch, which, in the present instance is of the knife type, said switch being in circuit with the motor 8 to control the 100 starting and stopping of said motor. The switch member 37 has connection through a thrust-rod 38 with the movable part 39 of a pneumatic operating unit 40 and has connection through a thrust-rod 41 with a movable part 42 of a pneumatic operating unit 43, whereby a collapsing movement of the movable part of the unit 40 in the present instance will move the switch member to circuit closing position and a collapsing 105 movement of the movable part of the unit 43 will move the switch part to circuit opening position. The units 40 and 43 are of the same type as shown in Fig. 3 and each has its suction passage 17 in communication through tubes 44 and 45, respectively, with the suction conduit 6. The passage 20 of the unit 40 has communication with the atmosphere through a tube 46, the outer or inlet end of which is normally closed to the 110 atmosphere by a valve 47. This valve, which is of any suitable type, is manually controlled for this purpose as its stem is provided in the present instance with a push button 48 that is placed within convenient 115 reach of the operator. A spring 49 serves to yieldingly close the valve 47.

The passage 20 of the switch operating unit 43 has communication with the atmosphere through a tube 50, which has its 120

inlet end normally closed to the atmosphere by a valve 51. This valve has its stem 52 provided with a shoulder 53 between which and a portion of the outlet end of the tube 50 is disposed a compression spring 54, which serves to yieldingly retain the valve 51 in closed position as shown. The valve 52 is also provided with a push button 55 which may be pressed by the operator to 10 effect a manual opening of the valve 51.

In order that the valve 51 may be automatically opened when the last sheet of a pile has been removed from the table 1, I provide the table 1 with an opening 56 in 15 register with the interior of each picking up mouth piece 4 when the mouth pieces have been swung inwardly to sheet picking up position. These openings 56 have communication through a tube 57 with the interior 20 of an ordinary collapsing bellows 58, the movable part of which has an arm 59 projecting therefrom and in engagement with the valve stem 52, whereby a movement of said arm, which is effected by a collapsing 25 of the bellows, will impart an opening movement to the valve 51. This automatic means for opening the valve 51 is not operative until the last sheet of a pile has been removed from the table 1 and the mouth 30 pieces 4 lowered to sheet picking up position. When so lowered the mouth pieces rest over the openings 56 in the table 1 and coöperate with the tube 5 to open communication between said openings and the suction conduit 6, it being understood that the valve 29 in the tube 5 then stands in open 35 position. The closing in this manner of the communication between the tube 57 and suction conduit 6 effects a collapsing of the bellows 58 and a consequent opening of the valve 51 to the atmosphere, thus permitting atmospheric pressure to enter the operating unit 43 through the tube 50 to effect a collapsing of the movable part 43 of such unit 40 and a consequent opening of the motor switch to stop the running of the motor.

It is evident that I have provided a stop mechanism for the actuating means of sheet printing or feeding apparatus, which means 45 is automatically operable to stop the actuating mechanism when the last sheet of a pile has been removed from a supporting part, or is manually operable to stop the operating of the actuating mechanism at any time.

I wish it understood that my invention is not limited to any specific construction, arrangement or form of the parts except in so far as such limitations are specified in the claims.

While I have particularly referred to the operation of the pneumatic units as being effected by the admission of atmospheric pressure to the passages 20 thereof, it is not intended to restrict the invention in this respect, as such operation is effected by the

admission to the passages 20 of the units of a fluid pressure, whether such pressure be atmospheric pressure or obtained by mechanical or other means. It will therefore be understood that the term, "atmospheric pressure," as used in the specification and claims has a generic meaning and has reference to the opening of the passages 20 of the operating units to any source of fluid pressure which is greater than the pressure in the chambers 16 of the operating units. 70

Having thus described my invention, what I claim as new, and desire to secure by Letters Patent, is—

1. In combination, an actuating means, a sheet holding table having an opening adapted to be covered by a pile of sheets carried thereby, a sheet picking up mechanism having a hollow mouth piece through which suction takes place, said mouth piece adapted to close over said table opening after the last sheet of a pile has been removed from the table, and means pneumatically operable to stop said actuating means when a suction is created in said table opening from within said mouth piece. 80

2. In combination, an actuating means, a suction device, a sheet holding table having an opening adapted to be covered by a pile of sheets carried thereby, a sheet picking up mechanism having a suction mouth piece in valve controlled communication with said suction device and movable into position to seat closely over said opening when the last sheet of a pile has been removed from the table, and means pneumatically operable to stop said actuating means when a suction is created in said table opening from within said mouth piece. 95

3. In combination, an electric motor, a control switch for said motor, pneumatically operating means for opening said switch, a sheet holding table having an opening, means interposed between said opening and said operating means and operable by a suction action in said opening to effect a switch opening operation of said operating means, a suction device, and a sheet picking up mechanism having a suction mouth piece in communication with said suction device and adapted to close over and create a suction through said table opening after the last sheet of a pile has been removed from the table. 105

4. In combination, an actuating mechanism, means pneumatically operable to stop said mechanism upon the opening of an interior part thereof to atmospheric pressure, a valve controlling the opening of said part, a sheet holding table having an opening therein which is covered by a pile of sheets on the table, means pneumatically operable by suction action in said opening to effect an opening of said valve, and means automatically operable after the removal of the 110

last sheet of a pile from said table to create a suction within said table opening.

5. In combination, an electric motor, a switch for said motor, means pneumatically operable to move said switch to open position to stop the motor when an interior part of said means is opened to atmospheric pressure, a valve normally closing said interior part to the atmosphere, a sheet holding table having an opening therein adapted to be covered by a pile of sheets on the table, means pneumatically operable to open said valve when suction occurs in said table opening, and sheet delivering means having a suction pick up member which closes over and creates a suction in said opening when the last sheet of a pile has been removed from said table.

6. In combination, an actuating means, a movable control part for said means, a unit pneumatically operable to move said part to starting position when an interior portion of said unit has been opened to atmospheric pressure, and a manually controlled valve normally closing said interior portion of said unit to the atmosphere.

7. In combination, an actuating mechanism, a control part for said mechanism, a suction device, means having communication with said suction device and operable to move said control part to open position when communication has been opened between an interior portion of said means and the atmosphere, and a manually operable valve for closing the communication between the atmosphere and the interior portion of said means.

8. In combination, a motor, a control part for said motor, a table having an opening therein adapted to be covered by a pile of sheets on the table, a pneumatic sheet delivery mechanism, and mechanism operable in cooperation with said sheet delivery mechanism to effect a movement of said control part to stop the motor after the last sheet of a pile has been removed from said table.

9. In combination, a motor, a control part for said motor, a sheet holding table having an opening adapted to be covered by a sheet carried thereby, a sheet feeding mechanism having valve controlled suction parts for intermittently picking up and delivering

sheets from said table, and mechanism pneumatically operable in cooperation with said sheet delivery mechanism to effect a moving 55 of said control part to stop the motor after the last sheet of a pile has been removed from over said table opening, said last mentioned mechanism having a part which is manually operable to effect an operation of 60 the mechanism to move said control part.

10. In combination, a sheet holding table, a suction device, a sheet picking up device, a pneumatically operated unit having a movable part, said unit having communication with said suction device and valve controlled communication with the atmosphere and being operable to effect a positive movement of said movable part when communication is opened with the atmosphere, and a 70 member connected to said movable part and means for communicating movement from one to the other.

11. In combination, a motor, a control part for said motor, a suction device, a pneumatically operable unit having communication with said suction device and manually controlled communication with the atmosphere and operable to move said control part to motor running position when communication is established between the atmosphere and an interior portion of said unit, a second pneumatically operable unit having communication with said suction device and valve controlled communication 85 with the atmosphere and operable to move said control part to motor stopping position when communication is established between the atmosphere and an interior part of said second unit, a sheet holding table, and means 90 pneumatically operable after the removal of the last sheet of a pile from the table to effect an opening of the communication between the atmosphere and the interior of said second unit to effect a movement of the control part to motor stopping position.

In testimony whereof, I have hereunto signed my name to this specification in the presence of two subscribing witnesses.

PHILLIP JACOB DREHER.
